Primary Examiner—Carol Rademaker(74) *Attorney, Agent, or Firm*—Ladas & Parry LLP(57) **CLAIM**

The ornamental design for a bottle, as shown and described.

DESCRIPTION

FIG. 1 is a front right side perspective view of a bottle having the design;

FIG. 2 is a front elevation view thereof, the rear elevation view being a mirror image thereof;

FIG. 3 is a right side elevation view thereof, the left side elevation view being a mirror image thereof;

FIG. 4 is a top plan view thereof, the inside bottom surface seen through the circular pour spout opening forming no part of the claimed design; and,

FIG. 5 is a bottom plan view thereof.

The broken line showing in the drawings of a bottle cap is included for the purpose of illustrating environmental structure and forms no part of the claimed design.
